UNITED STATES PATENT OFFICE.

HENRY G. SHOOK, OF NEW YORK, N. Y.

DESIGN FOR CANS.

Specification forming part of Design No. 6,872, dated September 2, 1873; application filed May 31, 1873.
[Term of Patent 3½ years.]

To all whom it may concern:

Be it known that I, HENRY G. SHOOK, of New York, N. Y., have invented a Design for Cans, of which the following is a specification:

The nature of my design is a new and useful and original shape or configuration of a can, caddy, and canisters, as represented in the accompanying drawings, consisting of three swells or curves on the front, as follows: One large center swell or curve, *a*, and two smaller outside swells or curves, *b b*, with a swelled or curved lid, *d*, opening and closing on two swelled or curved guards, or what tinsmiths call "boss-pieces," *c c*, extending and swelling from the front to the top of the caddy, as seen in Fig. 3.

Figure 1 represents the shape of the bottom of the caddy. Fig. 2 represents the front view. Fig. 3 represents a three-quarter and

side view. Fig. 4 represents a side view. Fig. 5 represents the front and lid, which is the part of the caddy which I claim as my invention.

I am aware that cans, caddies, and canisters have been in use for a long time; and I do not claim them. Nor do I claim the same with one swell or curve on the front from side to side.

What I claim as my invention is—

A design for a can or caddy having on the front thereof the large center curve *a* and the two smaller outside curves *b b*, with the inclined curved lid *d*, closing on the two curved guards *c c*, and the closed horizontal part of the top, substantially as described and shown.

HENRY G. SHOOK.
